COMBINED SEAT AND VIBRATABLE REED MUSICAL INSTRUMENT

Joseph Raymond Esquina, 11442 Angell St., Norwalk,
Calif. 90650, and James Daryl Addy, 2403 Seville
St., Anaheim, Calif. 92806

Filed Jan. 7, 1971, Ser. No. 104,840

Term of patent 14 years

Int. Cl. D17—03

U.S. Cl. D56—1

The single figure is an end, top and front perspective view of a combined seat and vibratable reed musical instrument, showing my new design.

The rear, bottom and opposite end, not shown, are unornamented.

We claim:

The ornamental design for a combined seat and vibratable reed musical instrument, as shown and described.
